UNITED STATES PATENT OFFICE

171,178

THREE-WHEELED TRACTOR

Byron T. Aasland and Merle W. Bloom, Kankakee,
and William L. Zink, Plano, Ill., assignors to
Sears, Roebuck and Co., Chicago, Ill., a corpo-
ration of New York

Application May 21, 1953, Serial No. 25,161

Term of patent 14 years

(Cl. D14—3)

To all whom it may concern:

Be it known that we, Byron T. Aasland, Merle W. Bloom and William L. Zink, have invented a new, original, and ornamental Design for a Three-Wheeled Tractor, of which the following is a specification, reference being had to the accompanying drawings, forming a part hereof.

Fig. 1 is a side elevational view of the three-wheeled tractor embodying our new design.

Fig. 2 is a front elevational view thereof.

Fig. 3 is an opposite side elevational view thereof.

Fig. 4 is a top plan view thereof.

Fig. 5 is a rear elevational view thereof.

We claim:

The ornamental design for a three-wheeled tractor, as shown.

BYRON T. AASLAND.
MERLE W. BLOOM.
WILLIAM L. ZINK.
